UNITED STATES PATENT OFFICE.

SAMUEL F. NEWMAN AND JAMES G. HARPER, OF WAYNESBORO, PENNSYLVANIA, AS
SIGNORS TO LANDIS MACHINE COMPANY, OF WAYNESBORO, PENNSYLVANIA, A
CORPORATION OF PENNSYLVANIA.

DIE HEAD.

Application filed August 11, 1922. Serial No. 581,180.

Our said invention consists in certain improvements on an automatic stationary die head for cutting threads in pipes and bolts, certain features being also applicable in other locations to perform similar functions. The 5 patent to Miller No. 1,296,546, March 4, 1919, shows a somewhat similar structure.

The object of our invention is to provide improved means for opening the cutter jaws 10 of the head.

Referring to the accompanying drawings which are made a part hereof and on which similar reference characters indicate similar parts,

Figure 1 is a face view of the device partly 15 in section,

Figure 2 a section on line 2—2 of Figure 1, Figure 3 a section on line 3—3 of Figure 1,

Figure 4 a face view of a modification,

Figure 5 a section on line 5—5 of Figure 4, 20 and

Figures 6 and 7 details of parts shown in Figure 1.

In the drawings 10 indicates a shank having a concentric flange 11, the shank being shown as hollow, though a solid shank may be used if desired. A ring 12 is held against rotation relative to the flange by means of pins including a pair shown at 13 and 14, these 25 pins permitting longitudinal movement of the ring relative to the shank as in the above mentioned patent. An opening ring 15 is adapted for rotation relative to the parts heretofore enumerated and is movable longitudinally 30 with the ring 12, rotation being normally prevented by engagement of reduced extensions 16 on the pins with openings in the ring 15 and said openings having renewable hardened bushings 17. The extensions 16 (Fig. 6) 35 are reduced at opposite sides to form arcs of circles corresponding to the circle of the hole in bushing 17. In this way the sides of the pins fit the inner sides of the bushings without any line contact. The rings 12, 15, 21 with 40 the flange 11 and the shank 10 constitute supporting means for a body 18 located within said rings and said flange and said body is adapted to move longitudinally with rings 12, 15 and 21. Relative longitudinal movement between said body and the rings 12 and 15 is prevented by the flange 19 at the forward end and a collar 20 at the rear end located in an annular recess of the body and 45 fixed thereto, said ring bearing against the

rear end of a thin ring 21 extending between 55 ring 12 and flange 11 and having a rearward extension over the flange 11 to close the joint between the adjacent parts. In some cases, and particularly in the smaller heads the ring 21 and collar 20 may be made in one piece. 60 The joint between the body and the shank at the inner side is closed by a bushing 22.

The body has longitudinal bores for supporting trunnions 23 each of which supports a block 24 carrying a cutter or chaser 25 and each block having a pin and slot connection at 65 26 with the ring 15. By this arrangement a rotary movement of the ring serves to open and close the jaws while rotary adjustment of the body by means of a worm engaging the 70 worm teeth 27 serves for adjustment of the cutters, the extent of the rotary adjustment being indicated as in our copending application No. 580,210 of even date herewith.

The resistance of the body being operated 75 on by the cutters may be relied on to open the same but it is preferred to add thereto the pressure of a spring or springs. In the present embodiment of our invention the opening ring 15 has a longitudinal opening or cavity 80 at 28 to accommodate a pin 29 or other suitable abutment fixed to the ring 12 and having a flattened end as shown in Figures 1 and 3. Cylindrical lateral passages 30 lead in opposite directions from the cavity 28 and are 85 threaded adjacent their outer portions. A spring 31 fits within either one of said passages according to the direction of cut, the head being provided with either right or left-hand cutters as the exigencies of the situation 90 require. The spring is held in place and the compression thereof is adjusted by means of threaded plug 32. The opposite opening is closed by a similar threaded plug 33 to keep 95 out dirt.

In Figures 4 and 5 reference characters 10', 12', 14', 15' and 21' indicate parts corresponding to those shown in Figures 1, 2 and 3. In this modification the pin 29' is fixed in the closing ring 15' and the spring 31' is located 100 in a cavity of the ring 12'. As in the previous modification the spring is adapted to be inserted from either side to bear against one of the flat sides of pin 29' and at its free end extends into a central recess of a threaded plug 32' engaging a threaded annular ledge 34. A second plug 33' engages a similar ledge at the 105 opposite side of the pin and change of loca-

tion of the two plugs and the spring serves to adapt the head for either right-hand or left-hand cutting as in the modification above described.

The operation of the device is similar to that described in our co-pending application No. 580,210 of even date herewith. The head body 18, with rings 15, 12 and 21 are adapted to be moved forward away from flange 11 10 as a unit. As the extensions 16 are freed from bushings 17, the ring 15 due to the back pressure of the cutters engaging the work abetted by the action of spring 31 rotates on the body to open the head, and this can be closed by 15 moving handle 35 to effect a reverse movement of the ring 15. Minor adjustments are made by a worm on ring 12 engaging teeth 27 to rotate the head as in the Miller patent, and the extent of such rotation may be indicated by a scale on flange 11 and a zero 20 mark on ring 21 which is forced to rotate with the body by a pin 36 locking collar 20 to ring 21, or by any other similar means.

In small dies we prefer to use trunnions 25 with cutter-holding blocks integral therewith. Pin 13, as in my co-pending application No. 580,210, may be arranged to give a rough and a finishing cut or may be the same as pins 14. These and various other 30 changes may be made in our device without departing from the spirit of the invention, the true scope of which is indicated in the appended claims.

Having thus fully described our said invention, what we claim as new and desire to secure by Letters Patent, is:

1. In a die head, a body, a shank having a forwardly directed flange, rings carried by the shank surrounding the body and movable therewith longitudinally of the head including a ring rotatable relatively to the body for opening and closing the head, a thin ring next to said flange abutting against a shoulder on the body, and a removable outer collar at 45 the rear end of the body abutting against the rear face of said thin ring substantially as set forth.

2. In a die head, a body, a shank having a forwardly directed flange, rings carried by 50 the shank surrounding the body and movable therewith longitudinally of the head including a ring rotatable relatively to the body for opening and closing the head, a thin ring next to said flange abutting against a shoulder on the body, a removable outer collar at the rear end of the body abutting against the rear face of said thin ring, and means for securing said thin ring and said collar to the body whereby said parts are rotatable and 55 adjustable with the body relatively to the remaining parts, substantially as set forth.

3. A die head comprising a shank, a head body normally rigid therewith, tangential chasers on the head body, a ring rotatable 60 about the head body for opening and closing

the die head said ring having a longitudinal opening and aligned passages extending therefrom to its periphery, an abutment rigid with the head body said abutment extending into said opening, a coiled spring adapted to be 70 located in either passage to bear against such abutment at its inner end, and means to hold the spring in place in either passage, substantially as set forth.

4. A die head comprising a head body 75 elongated, tangential chasers carried thereby, said chasers having parallel serrations on a long face, rings encircling the body including an oscillatory ring for opening and closing the head, said rings being movable with 80 respect to the head body, a pin on one of said rings extending into a cavity in another ring, and a spring extending from said cavity to the periphery of said rings and acting on said pin to move said rotatable ring in a 85 direction for opening the head, substantially as set forth.

5. A die head comprising a shank, a body normally held against rotation relatively thereto, cutters mounted on said body, a plurality of rings encircling said body including an oscillatory ring for opening and closing said head, a pin carried by one of said rings said pin extending into a cavity in another ring, a passage extending from said cavity 95 to the periphery of the last-named ring, a spring in the passage, and a plug having threaded engagement with the walls of said passage, substantially as set forth.

6. A die head comprising a shank, a body 100 normally held against rotation relatively thereto, cutters mounted on said body, a plurality of rings encircling said body including an oscillatory ring for opening and closing said head, a pin carried by one of said rings said pin extending into a cavity in another ring, oppositely directed passages extending from the cavity to the periphery of the ring, a spring adapted to be located in either one of said passages, and a plug adjustable in either of said passages to engage the spring and to vary the compression thereof, substantially as set forth.

7. In a die head, a head body, rings surrounding the body, an integral circumferential flange at the end of the body for holding the rings in place, a shoulder on the said body, a thin ring surrounding said body and adapted to rest against said shoulder, a thin ring secured to said body for securing said first-named thin ring in position, and a supporting shank for the body bearing against the rearmost ring, said shank being movable axially relatively to said ring, substantially as set forth.

8. A die head comprising a head body, rings surrounding the body, an integral circumferential flange at the end of the body for holding the rings in position, a pin rigidly secured in one of said rings, springs posi- 130

tioned in a bore extending from the periphery of the other ring and adapted to abut against the said pin for causing relative rotation of the rings, and a supporting shank for the 5 body bearing against the rearmost ring, said shank being movable axially relatively to said ring, substantially as set forth.

9. In a die head, a head body, an integral circumferential flange at the front end of the 10 body, a ring surrounding the body and held thereon by the said flange and relatively rotatable with respect to the head body, additional rings surrounding the head body and secured thereto, a pin fixed in one of said 15 rings and extending into a cavity in another of said rings, a spring inserted in a bore extending from said cavity to the periphery of said ring and adapted to rest against the said pin for causing relative rotation of the rings, 20 a shoulder on the body, a thin ring secured to the body and adapted to hold the rearmost ring securely against axial movement with respect to the body, and a supporting shank for the body having a flange bearing against the 25 rearmost ring on the body, substantially as set forth.

10. In a die head, a head body, rings surrounding the body, an integral circumferential flange at the end of the body for holding 30 the rings in place, a shoulder on the body, a thin ring surrounding said body and adapted to rest against said shoulder, a second thin ring secured to said body for securing said first-named thin ring in position, and a sup- 35 porting shank for the body bearing against the rearmost ring, said shank carrying blunt end pins adapted to move into and out of recesses in the forward ring for engaging and disengaging the ring, substantially as set forth.

11. A die head comprising a body member having a peripheral flange on the front end, a ring surrounding the body and held against axial movement by the flange, a second ring 40 on the body adjustably fixed thereto, a sup- 45 porting shank for the body having a forwardly extending flange surrounding the

rear end of the body, blunt end pins carried by said shank and adapted to seat in recesses in the first-named ring to hold the rings in 50 position during cutting operations, and means comprising a spring seated in a peripheral bore for causing relative rotation of the first and second-named rings upon disengagement of the pins from the bores, sub- 55 substantially as set forth.

12. A die head comprising a head body, threading cutters mounted thereon, a plurality of rings encircling said body said rings being connected to said threading cutters 60 and rotatably adjustable relative to the body for controlling the cutting size of said die head, one ring of said plurality of rings being rotatable independently of said body and the remainder of said rings, for opening the 65 threading cutters, a spring operating between said ring and the remainder of said plurality of rings, whereby upon relative rotation of the said plurality of rings and the said head body for size adjustment the tension of 70 said spring will remain uniform, substantially as set forth.

13. A die head comprising a head body, threading cutters mounted thereon, a plurality of rings, including an opening ring 75 encircling said head body, said rings being rotatively adjustable relative to the said body to vary the cutting size of said die head, the opening ring being rotatable independently of the remaining rings, a spring mounted be- 80 tween said opening ring and the remainder of said rings for imparting rotative movement to the opening ring for opening the head, said spring maintaining a fixed tension throughout the adjustment of said plurality 85 of rings around said head body for size adjustment, substantially as set forth.

In witness whereof, we have hereunto set our hands at Waynesboro, Pennsylvania, this twenty-ninth day of July, A. D. nineteen 90 hundred and twenty-two.

SAMUEL F. NEWMAN,
JAMES G. HARPER.
